Primary Examiner — Marianne Pandozzi*Assistant Examiner* — Jae Liang(74) *Attorney, Agent, or Firm* — Daniel V. Thompson**CLAIM**

The ornamental design for a dual chamber drink container, as shown and described.

DESCRIPTION

FIG. 1 is a front perspective view of a dual chamber drink container showing our new design;

FIG. 2 is a left-side elevational view thereof;

FIG. 3 is a front elevational view thereof;

FIG. 4 is a right-side elevational view thereof;

FIG. 5 is a rear elevational view thereof; and,

FIG. 6 is a top-plan-view thereof.

The broken lines in the figure drawings are for the purpose of illustrating portions of the dual chamber drink container and forms no part of the claimed design.
